(57) **CLAIM**

The ornamental design for a outdoor lighting fixture, as
shown and described.

DESCRIPTION

FIG. 1 is a front elevational view of a outdoor lighting fixture
according to my design, the rear and side elevational views
each being a mirror image thereof;

FIG. 2 is an overhead perspective view thereof;

FIG. 3 is a perspective view from below thereof;

FIG. 4 is a bottom plan view thereof; and,

FIG. 5 is a top plan view thereof.
